UNITED STATES PATENT OFFICE.

CLAIBOURNE FREMONT JACKSON, OF LAS MINAS, CUBA.

NON-REFILLABLE BOTTLE.

1,156,360.

Specification of Letters Patent. Patented Oct. 12, 1915.

Application filed September 30, 1914. Serial No. 884,319.

To all whom it may concern:

Be it known that I, CLAIBOURNE FREMONT JACKSON, a citizen of the United States, residing at Las Minas, Republic of Cuba, have 5 invented certain new and useful Improvements in Non-Refillable Bottles, of which the following is a specification.

This invention relates to a non-refillable bottle and the principal object of the invention is to provide an indicator which will be held in a raised position by the cork when the bottle is closed and which will drop into the bottle when the cork is removed.

Another object of the invention is to so 10 construct the indicator that a portion of the outer link will be broken off before the cork can be removed, thus causing the indicator to be released when the cork is extracted.

This invention is illustrated in the accompanying drawings wherein—

Figure 1 is a vertical sectional view through a bottle provided with the improved indicator; Fig. 2 is a top plan view of the bottle shown in Fig. 1; Fig. 3 is a 25 perspective view of a portion of the outer link.

The bottle 10 is provided with the usual neck 11 into which the cork 12 fits. This bottle may be of any suitable size and 30 threaded but must be made of some transparent material such as glass or the like so that the indicator may be readily seen. The rod 13 which forms the lower link of the indicator is embedded in the enlargement 14 formed in the bottom of the bottle and is 35 connected with the rod 15 or outer link by means of the links 16 and 17, the links being loosely connected by the eyes 18 so that when the cork is removed, the indicator may 40 be collapsed and fall to the bottom of the bottle. The rod 15 which carries the weight 19 has its free end portion 20 flattened as shown in Fig. 3, thus forming a bill which extends between the cork and the neck of the 45 bottle as shown in Fig. 1. The rod 15 is formed of some relatively brittle material so that when the bottle is opened, the bill will break close to the neck, thus preventing the indicator from being held in a suspended 50 position and also preventing the bottle from being refilled and a new cork put in place of the one which has been withdrawn.

When the bottle is being filled, the indicator is held in the vertical position shown 55 in Fig. 1 and the cork 12 is then put in place. After the cork has been put in place, the

bill 20 is bent to extend across the cork as shown at 21, with its tapered end portion 22 bent to form a spur 23 which is driven between the cork and bottle neck as clearly 60 shown in Fig. 1. The bill will now form a seal for holding the cork in place, it only being possible to withdraw the cork by first bending the bill back toward its original position. When doing this, the bill will 65 be broken at the point 24 and it will therefore be impossible to refill the bottle without it being shown. When the cork is withdrawn, the rod 15 will no longer be supported and therefore the indicator will collapse 70 and fall to the bottom of the bottle.

It will therefore be seen that a very simple indicator has been provided, the indicator not only serving the purpose of an indicator but also serving as a seal to hold the 75 cork in the bottle.

What is claimed is:—

1. A bottle provided with an outlet neck, a stopper fitting within said neck, and an indicator, said indicator comprising an inner link mounted in the bottom of said bottle, an outer link having its free end portion flattened, the outer link being formed of brittle material, a weight carried by said outer link, links connecting said outer link 80 with said inner link, said outer link being passed between said stopper and bottle neck, and being then bent to extend across said stopper and having its end portion bent and driven between said stopper and bottle neck. 90

2. A bottle provided with an outlet neck, a stopper in said outlet neck, and an indicator formed of a plurality of links, the inner link being mounted in the bottom of said bottle and the outer link being formed of 95 brittle material and having its free end portion flattened and passed between said stopper and bottle neck and being then bent to extend across the said stopper and having its end portion bent and driven between said 100 stopper and bottle neck.

3. A receptacle provided with an outlet neck, and an indicator within said receptacle formed of a plurality of loosely connected links, the inner link being embedded in the 105 bottom of said bottle and the outer link being formed of brittle material and having its free end portion flattened whereby the flattened portion of the outer link may be bent to secure a stopper in said neck and broken when bent to permit the stopper to 110 be removed.

4. A receptacle provided with an outlet neck, and an indicator positioned within said receptacle and formed of a plurality of links, the inner link being connected with said receptacle and the outer link being formed of breakable material whereby the outer link may be passed through the outlet neck and bent to secure a stopper within the outlet neck and broken when bent in an opposite direction to permit of the withdrawal of the stopper.

5. A receptacle provided with an outlet neck, a stopper in the outlet neck of said receptacle, and an indicator including a plu-

rality of links, the inner one of said links being connected with the body portion of said receptacle and the outer one of said links being formed of breakable material and being passed between said stopper and the outlet neck of said receptacle and bent to extend across the outer end of said stopper.

In testimony whereof I affix my signature in presence of two witnesses.

CLAIBOURNE FREMONT JACKSON.
